UNITED STATES PATENT AND TRADEMARK OFFICE
Certificate

Patent No. D.600,483 S

Patented: September 22, 2009

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: John R. Hamilton, San Rafael, CA (US); Karl J. Mead, East Grand Rapids, MI (US); and Andre K. Dettler, Brooklyn, NY (US).

Signed and Sealed this Thirtieth day of November 2010.
